UNITED STATES PATENT OFFICE.

JOHN H. DAVIS, OF LEXINGTON, KENTUCKY, ASSIGNOR TO CHARLES O. HADLEY, OF PHILADELPHIA, PENNSYLVANIA.

DESIGN FOR A FLEXIBLE SHOE-HORN.

57,115.

Specification for Design.

Patented Feb. 22, 1921.

Application filed June 17, 1920. Serial No. 389,770. Term of patent 7 years.

To all whom it may concern:

Be it known that I, JOHN H. DAVIS, a citizen of the United States, residing at Lexington, in the county of Fayette and State of Kentucky, have invented a new, original and ornamental Design for a Flexible Shoe-Horn, as shown in the accompanying drawing, forming part of this specification.

I claim:

The ornamental design for a flexible shoe horn, substantially as shown.

JOHN H. DAVIS.
